(57) **CLAIM**

The ornamental design for a plumbing fixture, as shown and described.

DESCRIPTION

In a preferred embodiment, the nature of this product is a plumbing fixture, such as a lavatory or portion thereof.

FIG. 1 is a top, left, front perspective view of a lavatory embodying my new design;

FIG. 2 is a top plan view thereof;

FIG. 3 is a front elevational view thereof;

FIG. 4 is a left side elevational view thereof, the right side elevational view thereof being a mirror image of the left side shown;

FIG. 5 is a rear elevational view thereof; and,

FIG. 6 is a bottom plan view thereof.

The broken line representations of a drain in FIGS. 1-6, holes in FIGS. 1-2, and 5-6, and of rear, internal and or underside structures in FIGS. 4-6 are for the purpose of illustration only, and form no part of the claimed design.
